UNITED STATES PATENT OFFICE

2,491,925

APPARATUS FOR ELECTROPLATING

Anton Lazaro, Chicago, Ill.

Application September 16, 1944, Serial No. 554,374

2 Claims. (Cl. 204—213)

1

The present invention relates to apparatus for electroplating and is particularly concerned with apparatus of the type in which a multiplicity of relatively small articles may be placed in a perforated container and immersed in a plating solution while the container is continuously rotated to insure the uniform application of a plating to all parts of the surfaces of the articles.

One of the objects of the invention is the provision of an improved electroplating apparatus comprising a unitary structure which is provided with a driving motor, speed reduction gears, and a suitable barrel in which the apparatus is so constructed that when the barrel is partially immersed in the electroplating solution and rotated, the electroplating solution is impelled into the barrel and through the interstices surrounding the articles to be electroplated in such manner that the time for electroplating is decreased and the efficiency of the apparatus is considerably increased.

Another object of the invention is the provision of an improved electroplating barrel unit of the class described which is so constructed that all of the parts which come in contact with acids or other solutions are constructed of neutral acid-resistant material which is unaffected by plating solutions and which may be used for a long period of time without any substantial deterioration.

Another object of the invention is the provision of an improved electroplating apparatus which is simple and which includes a minimum number of separate parts so that there are a minimum number of bends and corners in which dirt and other foreign matter may accumulate.

Another object of the invention is the provision of an improved electroplating barrel unit of the class described, which is sturdy, capable of economical manufacture, and which permits a view of the articles while they are being plated, so that the operator can observe when the plating is finished without necessity for opening the barrel to make sure that the electroplating has been satisfactorily completed.

Another object of the invention is the provision of an electroplating apparatus including a motor driven barrel unit and a special supporting stand for supporting the barrel unit and a draining basket or screen in such manner that the gears and the barrel will never be damaged by being placed upon other supports than those intended for it.

Another object of the invention is the provision of an improved barrel construction for elec-

2

troplating apparatus in which the barrel is constructed of a minimum number of pieces of material and in which the barrel is provided with an improved closure and clamping apparatus for the closure whereby the fixity of the closure on the barrel is assured while the barrel is operating but the clamps may be readily released and the barrel opened for charging or discharging the articles that are being electroplated.

Other objects and advantages of the invention will be apparent from the following description and the accompanying drawings, in which similar characters of reference indicate similar parts throughout the several views.

15 Referring to the drawings, of which there are three sheets:

Fig. 1 is a side elevational view in partial section, showing the electroplating apparatus supported upon a frame unit provided with a drain basket into which the plated articles may be discharged;

20 Fig. 2 is a similar view of the same apparatus shown in connection with the electroplating tank and the electrode which not only effects an electrical connection but supports the barrel unit;

25 Fig. 3 is a front elevational view of the apparatus of Fig. 1;

30 Fig. 4 is a fragmentary sectional view taken on the plane of the line 4—4 of Fig. 3 looking in the direction of the arrows;

Fig. 5 is a fragmentary sectional view taken on the plane of the line 5—5 of Fig. 1 looking in the direction of the arrows; and

35 Fig. 6 is a fragmentary sectional view taken on the plane of the line 6—6 of Fig. 3 looking in the direction of the arrows.

Referring to Figs. 1 to 3, the electroplating apparatus preferably includes a motor-driven barrel unit which is indicated in its entirety by the numeral 10 and a supporting stand for holding this unit when it is not in the tank and which is indicated by the numeral 11 (see Fig. 1).

The frame for the barrel unit preferably comprises a pair of forwardly extending frame members 12, 13 and a pair of transversely extending frame members 14, 15. For example, the forwardly extending frame members 12 and 13 may consist of angles of any suitable metal, preferably non-corrodible, such as stainless steel, and they may be secured to the transversely extending frame members 14 and 15 by screws or bolts to form a substantially rigid rectangular frame.

Referring to the supporting frame 11, this is preferably also constructed of suitable metal as described with respect to the other frame. The

supporting frame 11 may consist of a pair of substantially trapezoidal side frames 16, 17. The side frames 16 and 17 may be made out of a single channeled member which is bent at right angles at 18, at an obtuse angle at 19, and at an acute angle at 20, the ends being joined by welding at a slightly obtuse or right angle at 21. This provides the side frames with a horizontal bottom frame member 22, an upright rear frame member 23, and a top frame member 24 which is slightly tilted so that the barrel is readily accessible between the front frame members 25 of the two side frames 16 and 17.

The two side frames 16 and 17 may be joined at the bottom by being welded to the transverse channels 26, 27 and at the top by being welded to the transverse channels 28, 29 and the length of these channels bears such a relation to the top frame members 14 of the barrel unit that the barrel unit may be inserted between the side frames with the projecting top frame members 14 and 15 resting on the top frame members 24 of the side frames 16 and 17.

The barrel unit is prevented from sliding down toward the back or top frame members 24 by the channel 28 at the rear left (Fig. 1) and the size of the barrel unit in general is such that its frame fits within the rectangular opening that is provided at the top of the supporting frame 11 by the frame members 24, 24, 28, 29.

The supporting frame 11 is preferably provided with a drain basket indicated in its entirety by the numeral 30. The drain basket 30 may be provided with a pair of side frame members 31, 32, joined by the longitudinally extending frame members 33, 34. These frame members of the basket 30 may be made of the same suitable metal or of wood. The bottom of the basket is preferably covered with a perforated draining member 35 which may consist of a suitable sheet of non-corrodible metal or galvanized metal provided with a multiplicity of apertures some of which are shown in Fig. 3.

The drain member 35 may be secured to the bottom of the frame members 31, 32, 33, at the left end of the basket, but it is preferably arranged to slope upward at the front portion 36 and is secured to the top of the frame member 34 so as to provide for the convenient emptying of the basket at this side.

The basket 30 rests on the transverse bottom frame members 26, 27, of the supporting frame 11 beneath the barrel unit 10 in position to receive the electroplated articles when the barrel is emptied. The backward tilt of the supporting frame leaves a wide opening at the front of the supporting frame 11, that is, at the right of Fig. 1, for removal of the basket with its plated articles and the apertures permit the solution to drain from the articles into a convenient tank or drain pan 37.

The supporting stand 11 also insures the adequate support of the electroplating barrel unit 10 when it is not supported in the tank and precludes the operator from damaging it by setting it upon its gears or other more fragile parts.

The barrel unit frame comprising the frame members 12 to 15 inclusive preferably supports a pair of depending bearing plates 38, 39 and these bearing plates, as well as all of the other parts of the electroplating unit which are apt to be immersed in the solution, are preferably made of a composition such as a modern plastic which is heat-moldable and adapted to resist deterioration or solution by acids, electroplating solutions,

or any other materials with which they might come in contact. For example, I prefer to make these parts of a plastic of the type known as acrylicite plastic, produced by polymerization of the monomeric derivatives of acrylic and methacrylic acids, which is substantially transparent and is heat moldable and resistive to most reagents.

Bearing plates 38 preferably have their top edges 40 straight so that they may engage the upper flanges 41 of the angle members 12 and 13 to which they may be secured by screw bolts 42 passing through the apertures in the angles and threaded into the plates 38, 39.

The shape of these bearing plates may vary considerably but as they are intended to support the bearings for the electroplating barrel 43, plates 38, 39 may taper downwardly, having the converging lower edges 44, 45 terminating in a partially circular lower edge 46. Each bearing plate 38, 39 preferably supports a bearing block 47 which may consist of a piece of the same material having a cylindrical supporting portion 48 that fits into a cylindrical bore 49 in each plate 38 or 39. The supporting portion 48 carries a cylindrical trunnion 50 which projects from the supporting portion and has a rotating fit in a journal plate 51 and gear plate 106 carried by the opposite ends of the barrel 43. The trunnion block 47 may be secured in place by a pair of threaded members 52 of the same plastic material.

In order to provide for the connection of the articles to be electroplated into the electrical circuit, the barrel 43 is provided with one or more, preferably two, electrodes 53. The electrodes 53 have metallic heads 54 which may be cylindrical and which may have a conically pointed end portion 55. These electrodes are preferably made of non-corrodible metal such as nickel silver, or stainless steel.

Each electrode head 54 has an aperture 56 into which the stranded copper conductor 57 may be brazed and a counterbore 58 for receiving the rubber insulating cover 59 on this conductor. The insulated conductor passes through an enlarged cylindrical bore 60 in the end wall 61 of the barrel 43 and through a similar bore 62 in the bearing block 47 and end plate 38.

The conductor 57 may have its other end provided with a suitable connector 63 which is secured by means of a screw bolt 64 to a metal conducting strap 65. The screw bolt passes through both the connectors 63 and strap 65 and is threaded into the plastic plate 38.

Strap 65 is preferably made of copper or other suitable metal of high electrical conductivity and it is twisted at 66 so that its upper end is located in a plane at right angles to the lower end. Thus, the upper end portion may be bent to form a substantially rectangular hook portion 67 which fits over a supporting bus bar 68 comprising a cylindrical rod that is carried at the top of an electroplating tank 69 both for the support of the barrel units and for effecting the electrical connection to the electrodes 53.

The other electrical connection is made to the electrode of the metal which is used for electroplating. The electrodes 53 make contact with the various metal articles to be plated that are adjacent to them and through contact between the various articles all of these articles are electrically connected to electrodes 53. Of course the electroplating fluid of Fig. 5 covers both the electrodes and articles but the contact resistance

between the electrodes and articles is so much less than the resistance of the electroplating solution, that the major part of the current passes through the articles which are to be electroplated.

At the point 70 (Fig. 5) the strap 65 is provided with an offset so that it may be spaced sufficiently from the frame and motor housing to prevent interference between the supporting straps and this housing.

The electroplating barrel 43 is also preferably constructed of the same plastic material and the barrel may be constructed quite simply of four pieces of this material such as the two end plates 61, the main body plate 71, and the cover plate 72 (Fig. 6).

The end plates 61 may consist of a thick polygonal plate of this plastic material such as, for example, a hexagonal plate which is provided on one side with a groove 73 of substantially rectangular cross-section. The groove is spaced uniformly from the edge of the octagonal plate 61 and is adapted to receive the edges of the body plate 71 with a tight frictional fit. These parts may be welded together by the application of a cement of the same material under heat or otherwise, or they may be secured together by screw bolts of the same material.

The main body plate 71 may consist of a substantially rectangular sheet of this same material which is bent at a suitable obtuse angle at each of its corners 74—78 in such manner as to form a polygonal member with one open side. This may be done by the application of heat to the points where bending is desired and the bend is preferably an easy bend so that the container has rounded corners on the outside and inside.

The body plate 71 and cover plate 72 are all preferably provided with a multiplicity of through apertures 79 uniformly spaced from each other and extending diagonally through these members in such direction that the outside 80 of each aperture faces in the direction in which the barrel is turning and the inside 81 of each aperture faces in the direction from which the barrel is moving.

Thus, the apertures 79 are adapted to scoop the liquid into the barrel and it is found that there is a marked increase of circulation of plating liquid through the barrel due to the direction in which the apertures extend. The plating may be expedited and the time for electroplating substantially shortened by reason of the increased circulation of fluid through the barrel due to this structure.

As previously described, the edges of the main body plate 71 are located in the grooves 73 of end plates 61. At the side of the barrel where the opening occurs, the wall portion indicated at 82 (bottom Fig. 5) of the groove 73 may be removed and the cover may be made long enough to extend to the base 83 of the groove 73 and to engage the side wall 84 of this groove. Thus, the cover is of substantially the same length as the body plate 71 and its inner surface is beveled at 85 to fit against the ends of the body plate and close the aperture completely.

Cover plate 72 is preferably provided intermediate its ends with a handle plate 86 which projects outwardly therefrom and which may have depressions 87 for receiving the fingers. The cover plate 72 is preferably secured in place by suitable clamping members 88 one of which is shown in Fig. 6. Two of these clamping members are preferably employed although one may be sufficient if located near the center of the cover

plate 72. Each clamping member is preferably made of resilient spring material suitably plated to avoid corrosion or of resilient non-corrodible material.

5 Each clamp 88 has a central U-shaped portion 89 which gives it its main resilient characteristics. From the U-shaped portion 89 arms 90 and 91 extend in opposite directions and the corners 92, 93 between these arms and the U-shaped portion 89 engage the cover plate 72.

At each end arms 90, 91 are bent at an obtuse angle at 94, 95 so that the engaging portions 96, 97 lie flatly against the keeper bars 98, 99.

Engaging portions 96, 97 carry an inwardly bent retaining flange 100, 101 and the flange 101 may be of U shape so as to support a backwardly extending handle flange 102.

Flange 102 is for engagement with the fingers and when pulled away from the barrel 43, it will cause the flange 101 to slide off the keeper 99 and effect a separation of the clamp from the keeper strips 98, 99.

25 Keeper strips 98, 99 are straps of the same plastic material which are secured to the outside of the barrel adjacent the edges of the main plate 71. Keeper strips 98, 99 preferably project beyond the edges 103 of the opening so that the cover 72 may be seated above and below these keeper strips 98, 99.

30 The tension of the clamps 88 is provided by the U-shaped portion 89 which preferably tends to close together so as to draw the retaining members 100 and 101 toward each other. The clamp may be applied by hooking the retaining flange 100 over the keeper 98 and pressing downward upon the portion 88 until the portion 89 spreads and the retaining flange 100 passes over the edge of keeper 99.

35 The journal plate 51 at the right hand side of barrel 43 (Fig. 5) merely consists of a circular plate of the same plastic material having a centrally located aperture 104 serving as a bearing for receiving the trunnion portion 50 of the trunnion block 47 at this end of the barrel. Journal plate 51 may be secured to the end plate 61 by plastic screw bolts 105.

40 At the left end of the barrel 43 (Fig. 5) the journal plate 106 preferably consists of a circular gear member made of the same plastic material and provided with a similar aperture 104 serving as a journal for the trunnion 50.

45 Gear 105 is of considerable size to serve in reducing the speed of rotation of the barrel 43 and is provided with peripheral teeth 107 for engaging the teeth on a driving gear 108 which is carried by a shaft 109.

50 The motor unit which drives the barrel may be mounted upon a base plate 110 of the same plastic material which is secured to the transverse frame members 113 and 114 by means of suitable screw bolts 111. The motor is fastened to this base plate 110 by suitable screw bolts 112 and the motor is preferably provided with a unitary speed reducing gearing unit 113. This speed reducing gearing may comprise a suitable housing provided with bearings for the motor shaft 114, the drive shaft 109, and another vertical shaft 115.

55 The drive is from the motor shaft 114 which carries a worm 116 for engaging a worm gear 117 carried by shaft 115. Shaft 115 carries a second worm 118 which engages a worm gear 119 that is carried by shaft 109. Shaft 109 carries a spur gear 108 which drives the large gear 106.

60 The motor 120 is preferably of the induction type which is adapted to run without causing

static for radio reception and its shaft 114 may carry a plastic fan blade 121 at the end opposite to the gear housing 113. The motor is preferably covered with a U-shaped housing member 122 of the same plastic material which fits down against the base plate 110 and which is grooved at 123 to receive a pair of apertured housing end plates 124, 125. Air passes in at the apertures in one end plate 125 and out of the apertures of the other end plate to cool the motor and maintain it at suitable operating temperature.

The supporting straps 65 are preferably also provided with handle members 126 which extend oppositely to the hook members 67 and which are welded to the hook members so that the operator may grasp the handles 126 to lift the barrel unit out of the tank off the bus bar 68 to place it on the supporting frame 11.

The operation of my electroplating apparatus is substantially as follows: The barrel 43 may have its clamping members 88 removed, to remove the cover 72, and a suitable supply of small metal articles to be plated may be placed in the barrel. Then the cover may be reapplied and secured by means of the clamps and during this time the barrel unit is supported on the frame 11. It may then be removed by means of the handles 126 and placed with its hook connectors 67 on the bus bar 68 with the barrel in the tank 69. The barrel is preferably immersed in the electroplating solution to about one-third the depth of the barrel and then the motor 120 may be energized by plugging in its connector or by turning on a suitable switch.

The barrel will then be rotated at a slow speed and due to the polygonal nature of the barrel, the articles to be electroplated will be tumbled over and over into the solution while they are in electrical connection with the electrodes 53. During this time the electroplating solution is effectively scooped into the barrel by the apertures 79 which face in the direction of the rotation of the barrel and this so increases the circulation of the plating fluid through the barrel that the time for electroplating may be diminished from ten to fifteen per cent.

The present plating apparatus is constructed substantially completely of chemically inert plastic material which is unaffected by acids or other solutions with which it may come in contact. This material is hard enough to resist the wear of the articles within the barrel and thus the apparatus may be used for a long period of time without substantial deterioration.

The parts are preferably secured together by means of screws of the same plastic material so there is a notable absence of any corrodible metal in the electroplating tank.

The articles being electroplated may be observed while the plating is going on and the operator may also be assured that every barrel has a suitable charge and that it is suitably immersed in liquid.

It will thus be observed that I have invented an improved electroplating apparatus which is simple, sturdy and economically manufactured. My apparatus is more efficient than the devices of the prior art and has a minimum number of separate parts. It increases the visibility of the conditions under which electroplating is carried on and is adapted to increase the circulation of the plating fluid around the articles to be electroplated.

While I have illustrated a preferred embodiment of my invention, many modifications may

be made without departing from the spirit of the invention; and I do not wish to be limited to the precise details of construction set forth, but desire to avail myself of all changes within the scope of the appended claims.

Having thus described my invention, what I claim as new and desire to secure by Letters Patent of the United States, is:

1. In a self-contained portable electroplating barrel unit, the combination of a supporting frame comprising longitudinal and transverse metal frame members secured together to provide a rectangular frame with the longitudinal frame members projecting longitudinally therefrom, a driving motor carried above and by said frame, a transverse drive shaft carried by said frame and connected by speed-reducing gearing to the shaft of said motor, said drive shaft carrying a driving gear constructed of chemically inert initially plastic material, a pair of depending bearing brackets carried by said frame and extending parallel to each other, an electroplating barrel consisting of a pair of thick end plates, said end plates being grooved on their inner opposing sides and the said groove being of substantially the shape of a polygon, a single-sheet side wall for said barrel which is bent under the influence of heat at a plurality of obtuse angles, said angles being equally spaced from each other to form a regular polygon with the side edges of said body plate shaped to fit in said grooves, means for rotatably supporting said end plates on said depending bearing plates, said end plates, bearing plates and latter means being formed with an axial aperture at each end of the barrel, an insulated conductor secured to said depending plates and extending through said aperture at each end of the barrel and provided at its end with a metallic head which is socketed to receive the insulation of said conductor and counterbored to receive the conductor, a gear carried by one of said end plates and meshing the first-mentioned gear, said latter gears, depending plates and barrel all being made of said initially plastic chemically inert material and the ends of said barrel being integrally welded to the side edges of said body plate, a pair of hook shaped members of electrical conducting material carried by said depending plates and electrically connected to said insulated conductors for simultaneously supporting the unit on a bus-bar, and connecting the conductors and metallic members inside the barrel to one terminal of a source of direct current.
2. In a self-contained portable electroplating barrel unit, the combination of a supporting frame comprising longitudinal and transverse metal frame members secured together to provide a rectangular frame with the longitudinal frame members projecting longitudinally therefrom, a driving motor carried above and by said frame, a transverse drive shaft carried by said frame and connected by speed-reducing gearing to the shaft of said motor, said drive shaft carrying a driving gear constructed of chemically inert initially plastic material, a pair of depending bearing brackets carried by said frame and extending parallel to each other, an electroplating barrel consisting of a pair of thick end plates, said end plates being grooved on their inner opposing sides and the said groove being of substantially the shape of a polygon, a single-sheet side wall for said barrel which is bent under the influence of heat at a plurality of obtuse angles, said angles being equally spaced from each other

to form a regular polygon with the side edges of said body plate shaped to fit in said grooves, means for rotatably supporting said end plates on said depending bearing plates, said end plates, bearing plates and latter means being formed with an axial aperture at each end of the barrel, an insulated conductor secured to said depending plates and extending through said aperture at each end of the barrel and provided at its end with a metallic head which is socketed to receive the insulation of said conductor and counterbored to receive the conductor, a gear carried by one of said end plates and meshing the first-mentioned gear, said latter gears, depending plates and barrel all being made of said initially plastic chemically inert material and the ends of said barrel being integrally welded to the side edges of said body plate, a pair of hook shaped members of electrical conducting material carried by said depending plates and electrically connected to said insulated conductors for simultaneously supporting the unit on a bus-bar, and connecting the conductors and metallic members inside the barrel to one terminal of a source of direct current, and an electroplating tank of electrical insulating material containing an electroplating solution, said tank having a transversely extending bus-bar extending across its upper and open end

for receiving the hook shaped supporting members of said unit.

ANTON LAZARO.
